[57] CLAIM

The ornamental design for a shotgun head with integral
hanger hook, as shown and described.

DESCRIPTION

FIG. 1 is a side elevational view of a shotgun head with
integral hanger hook embodying my new design, the
opposite side thereof being a mirror image thereof;
FIG. 2 is a top view thereof;
FIG. 3 is a bottom view thereof;
FIG. 4 is a left end view thereof; and
FIG. 5 is a right end view thereof.

FIG. 1

FIG. 2

FIG. 3

FIG. 4

FIG. 5
